UNITED STATES PATENT OFFICE.

MICHAEL IVERSEN, OF STOUGHTON, WISCONSIN.

SURGICAL APPLIANCE.

1,111,587.

Specification of Letters Patent. Patented Sept. 22, 1914.

Application filed October 27, 1913. Serial No. 797,505.

To all whom it may concern:

Be it known that I, MICHAEL IVERSEN, a citizen of the United States, and a resident of Stoughton, in the county of Dane and State of Wisconsin, have invented a new and Improved Surgical Appliance, of which the following is a full, clear, and exact description.

This invention relates to improvements in surgical or medical appliances or apparatus and more particularly to a new and improved fountain especially adapted for use in douching, and characterized by an improved construction to permit the flow of a given amount of a fluid in a given time or a large quantity of such fluid for the purpose of giving enemas or constituting a proctoclysis apparatus.

A further object of the invention is the provision of an improved can or tank having an outlet in which are mounted a pair of valves or stop cocks, one of which is designed to be set at a certain adjustment for permitting the flow of a certain number of drops of the fluid per minute, especially in the case of proctoclysis when only 40-60 drops per minute are allowable generally, while the second valve is designed to permit the flow of the fluid or to cut off said flow passing through the first mentioned valve, whereby it is unnecessary to require readjustment of the first-mentioned valve, usually constituting an arduous task, for the discharge of the required quantity of fluid as in proctoclysis treatment, as distinguished from such treatments as above referred to in which both valves will be totally opened.

A further object of the invention is to provide a device for the purpose specified in which the discharge pipe communicating with the interior of the can near the bottom thereof has a tube connected thereto outwardly of the aforesaid valves, said tube extending upwardly and communicating with the interior of the can or tank near the top so as to constitute a handle by which the device may be carried or conveniently suspended, and also providing an auxiliary duct for the escape of the returned gases for the relief of flatus, the device being adapted for use with, and also being a specific improvement upon, the apparatus illustrated in my application Serial No. 712,836 allowed June 27, 1913.

With the above and other objects in view,

the invention resides more particularly in the peculiar combination and arrangement of parts which will be illustrated as a preferred embodiment in the accompanying drawings and described in the specification.

Reference is to be had to the accompanying drawing forming a part of this specification, in which the figure is a side elevation, partly in section, of the improved surgical appliance or fountain.

With the preliminary understanding expressed in the objects of the invention as an improvement upon the application in question, the illustrated embodiment is shown in the form of a fountain can or tank 10 of any suitable shape or preferably of circular contour in general outline but flattened at the back portion as shown at 11 to engage a vertical support or wall 12 and be steadily held thereagainst and supported by means of an apertured vertically extending projection or ear 13 by a nail or the like 14 engaged through the aperture 15. The can is preferably constructed of enameled metal, either tin or iron ware, and has a cover 16 fitted to normally close its upper end. By removing the cover the can may be filled very conveniently and to any required height, the cover being off while the device is in use.

Adjacent to its lower end the can is provided with an outlet or discharge opening around which is disposed a fitting 17 which may be provided with a threaded engaging portion 18 for the casing 19 of a turn valve or pet cock 20 constituting the inner controlling member adapted to be set at a particular adjustment to permit the flow of the required number of drops of fluid per minute, or in any other necessary quantity, but especially the former. Connected in a suitable way, such as is illustrated in the drawings, in spaced relation to the valve 20 is a casing 21 having a turn valve or pet cock 22 operating therein, the form of valve used having no special bearing upon the broad idea of providing the inner and outer controlling members to regulate the flow of the fluid through the outlet. The outer valve 22 is adapted more especially to be totally closed or opened for the purpose of permitting the free discharge of the fluid passing through the valve 20 or to entirely cut off the flow into and through the discharge tube 23 which is connected with the casing 21.

The tube 23 has a tube 24 communicating

therewith, said parts being formed integrally or otherwise and the tube 24 extending upwardly, in an inclined direction as illustrated if desired, and having a curved top portion 25 through the duct of which communication is made with the interior of the can. The tube 24 thus provides a convenient handle by which the receptacle or can may be carried and suspended in the 10 manner heretofore described. An important feature is that the tube 24 communicates with the tube 23 outwardly of the valves or pet cocks and they have a common communication for the attachment of a flexible tube and nozzle in the ordinary or any preferred manner. Thus, when the device is in use and it is desired to provide a free discharge of the fluid both of the valves are opened, but in the special adaptation of the 15 construction in question the inner valve is adjusted to discharge a given number of drops of the fluid per minute, or other number desired to be administered, the valve 22 operating to permit the flow or to entirely 20 cut off the same by operation independently of the valve 20. To provide relief against flatus or back pressure of the gases generated, it will be observed that through the instrumentality of the tube 24 two distinct 25 paths of communication are established with the interior of the can, and as the valve 20 provides a restricted communication and as the tube 24 is unobstructed, it is obvious that the air and gases will freely pass through 30 the tube 24 and into the receptacle to relieve 35 a patient and prevent displacement of the nozzle or instrument employed.

When the cover 16 is provided, it simply 40 serves to protect the contents of the can from dust and germs, when not being used. However, as the cover is always removed when the device is in use, so as to permit the free escape of the air and gases from the tube 24, the cover may be well omitted 45 without affecting the operation of the appliance.

Having thus described my invention, what 50 I claim as new and desire to secure by Letters Patent is:—

55 1. A fountain can comprising a receptacle having a supporting extension and a removable cover, a valve connected to the receptacle adjacent the bottom thereof and provided with a passageway extending horizontally therefrom, and another passageway adjacent the top of the receptacle and communicating with the first-mentioned passageway outwardly of the valve, said second passageway being inclined at a spaced distance 60 from the receptacle and being rigid.

2. A fountain can comprising a receptacle, a valve connected to the can adjacent the bottom thereof and provided with a passageway extending substantially horizontally therefrom, and another passageway 65 communicating with the interior of the receptacle adjacent the top thereof and with the first named passageway outwardly of the valve, said second passageway being inclined at a spaced distance from the receptacle. 70

3. A fountain receptacle of the class described, comprising a vessel having an outlet near its bottom provided with a discharge tube, a rigid tube communicating with the first-mentioned tube at a spaced distance 75 from the vessel and also communicating with the interior of the vessel near the top of the latter, said tube having rigid connections with the vessel and discharge tube, and providing a handle for the vessel and a return duct for the air and gases, and a pair of valves mounted in the outlet tube. 80

4. A fountain can comprising a receptacle having an open top, a valve connected to the 85 can adjacent the bottom thereof and provided with a passageway extending horizontally therefrom, another passageway adjacent the top of the receptacle and communicating with the first named passageway 90 outwardly of the valve, and a second valve mounted in the first named passageway outwardly of the first named valve whereby when the first named valve is set to permit the discharge of a predetermined quantity 95 of fluid, said fluid may be permitted to escape or be held from escaping at required intervals, further discharge of said predetermined quantity of fluid being permitted by operation of the outer valve alone. 100

5. A fountain can comprising a receptacle, a valve connected to the receptacle adjacent the bottom thereof and provided with a passageway extending outwardly therefrom, and another passageway leading 105 from the receptacle near its top and communicating with the first named passageway outwardly of the valve, said second passageway being positioned at a spaced distance from the receptacle throughout its length, 110 said receptacle being adapted to contain and discharge fluid through the first passageway under a hydrostatic pressure head.

In testimony whereof I have signed my name to this specification in the presence of 115 two subscribing witnesses.

MICHAEL IVERSEN.
